OTHER PUBLICATIONS

Office Action from Canadian Patent Application No. 159,586, mailed Apr. 17, 2015 (3 pages).

Primary Examiner — Kelley Donnelly(74) *Attorney, Agent, or Firm* — Leanna Taveggia Farrell; Westman, Champlin & Koehler, P.A.(57) **CLAIM**

The ornamental design for a display fixture, as shown and described.

DESCRIPTION

FIG. 1 is a perspective view of a first embodiment of a display fixture showing our new design;

FIG. 2 is a front view thereof;

FIG. 3 is a right side view thereof, the left side view being a mirror image; and,

FIG. 4 is a top view thereof.

The dash-dash-dash broken lines illustrate portions of the display fixture and form no part of the claimed design. The dash-dot-dash broken lines illustrate boundaries and form no part of the claimed design.

1 Claim, 4 Drawing Sheets(56)
